UNITED STATES PATENT OFFICE.

LUKE ANDERSON, OF LONDON, COUNTY OF SURREY, ENGLAND, ASSIGNOR
OF ONE-HALF TO LEICESTER BRADNEY STEVENS, OF SAME PLACE.

REVERSIBLE BACK-STOP.

SPECIFICATION forming part of Letters Patent No. 396,188, dated January 15, 1889.

Application filed August 21, 1888. Serial No. 283,380. (No model.) Patented in England February 23, 1887, No. 2,787, and in Belgium March 29, 1887, No. 76,900.

To all whom it may concern:

Be it known that I, LUKE ANDERSON, a subject of the Queen of Great Britain, residing at London, in the county of Surrey, England, have invented a certain new and useful Reversible Back-Stop for Revolving Shafts, (for which I have received Letters Patent in Great Britain, No. 2,787, dated February 23, 1887, and in the Kingdom of Belgium, No. 76,900, dated March 29, 1887,) of which the following is a specification, reference being had to the accompanying drawings.

My invention consists of a novel kind of back-stop, which can be used in place of the ratchet-wheel and pawl hitherto used for this purpose and can be applied to any kind of revolving apparatus.

In the drawings, Figure 1 is a plan view of the back-stop, and Fig. 2 is also a plan view showing a modification of the back-stop.

A is a revolving shaft, which may be the main shaft of a turnstile or any other device which is ordinarily supplied with a ratchet-and-pawl back-stop.

25 B is a toothed wheel secured upon shaft A. C is a pinion, which gears into the said wheel B and is revolved by it.

E is a fixed bracket.

The pinion C is retained in gear with the 30 wheel B by having its spindle journaled in the slot D of bracket E, as shown in Fig. 1, or it may be kept in gear by the arm D', one end of which encircles the shaft A.

The bracket E is provided with two holes, 35 F and F', one on each side of the pinion C, and G is a stop pin or plug which may be slipped into either of the said holes. The slot D permits the pinion C to vibrate, the amplitude of the vibration being limited by 40 the length of the slot. The arm D' also allows the pinion to vibrate, and the motion is limited by the stops H and H' upon the bracket E, against which the arm strikes.

When the shaft A is revolved in the direction of the arrow in Fig. 1, and the pin G is in the hole F at the left hand of the bracket, the pinion C is pushed to the right-hand end of the slot D by the motion of wheel B, and the pinion continues to revolve

as long as the revolution of shaft A is continued in the direction of the arrow. If the direction of the motion is reversed, the pinion C is pushed to the left-hand end of slot D and the pinion-teeth engage with the pin G, the pinion C and wheel B being thereby 55 both prevented from revolving.

The device is changed to operate in the reverse direction by merely changing the pin G from hole F to hole F'.

The operation of the modification shown in 60 Fig. 2 is precisely the same as that of the device shown in Fig. 1.

It is obvious that the back-stop may be arranged to work in one direction only by making the stop-pin G a fixture at either F 65 or F'.

What I claim is—

1. The combination, with a revoluble shaft, of a toothed wheel secured on the shaft, a laterally-movable pinion gearing into the 70 toothed wheel, and a stop adapted to engage with the said pinion and prevent the back motion of the shaft, substantially as set forth.

2. The combination, with a revoluble shaft, of a toothed wheel secured on the shaft, a 75 laterally-movable pinion gearing into the toothed wheel, a fixed bracket provided with a hole on each side of the pinion, and a removable stop adapted for insertion into either of the said holes for arresting the motion of 80 the pinion, substantially as and for the purpose set forth.

3. The combination, with a revoluble shaft, of a toothed wheel secured on the shaft, a fixed bracket provided with a central slot 85 and a hole upon each side of the slot, a laterally-movable pinion gearing into the said wheel and guided by the said slot, and a stop adapted for insertion into either of the said holes for arresting the motion of the pinion, 90 substantially as and for the purpose set forth.

In testimony whereof I have signed this specification in the presence of two subscribing witnesses.

LUKE ANDERSON.

Witnesses:

ALFRED DONNISON,
JOHN A. DONNISON.
